UNITED STATES PATENT OFFICE

KONRAD JAGSCHITZ, OF MAINZ, GERMANY, ASSIGNOR TO MASCHINENFABRIK AUGSBURG-NUERNBERG A.-G., OF NUREMBERG, GERMANY, A CORPORATION OF GERMANY

GASOMETER

Application filed July 22, 1928, Serial No. 380,005, and in Germany July 30, 1928.

My invention relates to gasometers of the telescoping type, and in particular to telescoping gasometers provided with sliding seals carried by the gasometer sections or 5 bells and adapted to slide against the inner or the outer surfaces of the adjacent overlapping bell to seal such bells against the escape of gas from the interior of the gasometer.

In telescoping gasometers provided with sliding seals between the individual bells, it is necessary that the latter be provided with smooth surfaces in order that the sealing means may slide upon the same without 10 obstruction and the seals thus remain unbroken. Consequently where such sliding seals are to be employed, it becomes inadvisable, if not entirely impracticable, so to 15 construct the gasometer sections that projecting rivet heads, horizontal overlapping of the plates of which the bells are composed, etc. occur, as the continuity and gas-tight 20 character of the seals are disturbed thereby. One way out of the difficulty, it might appear, 25 would be to build up the gasometer sections by welding the individual plates to each other, but this construction is insecure and difficult to accomplish because of the thinness of the plates commonly used.

Thicker plates may, of course, be employed 30 but it is uneconomical to use them merely for the sake of convenience in construction.

The present invention has for one of its 35 objects to provide a gasometer construction which overcomes these difficulties in a simple and economical manner, and at the same time presents a solution of the problem of mutually guiding the gasometer sections within each other, thereby making superfluous the 40 use of special guiding frame works.

In its broader aspect the present invention 45 relates to the sealing, guiding and reinforcing of telescopic gasometers, whether of the vertically or spirally moving type. The present invention aims essentially to simplify the construction of gasometers of this type and at the same time insure their complete reliability in operation. It is an important object of the invention to so construct 50 the individual bells of the gasometer

and the seals associated therewith, that certain parts, including the seals, perform a plurality of functions, so that the number of constructional elements is considerably reduced.

The present invention employs the known construction wherein the individual annular bells of the gasometer are built up of plates which are of the height of such bells. As a result, there are no horizontally extending 55 joints and the rows of rivets run only from top to bottom, i. e. in the direction of movement of the gasometer bells. In accordance with the present invention I apply reinforcing bars in the form of posts to both sides of the joints, such reinforcing bars making it possible to utilize sunken rivets even with very thin plates as they serve to receive the sunken rivet heads these bars serve in addition to stiffen the gasometer bells, and also 60 to act as guides for the latter during their rising and falling movement, as explained 65 hereinbelow. As these iron reinforcing bars have smooth surfaces and extend in the direction of movement of the gasometer bells, 70 they can penetrate the seals in such manner that the proper operation of the latter is not disturbed. For this purpose, suitable cut-outs are provided in the packing rings of the 75 seal, against which cut-outs the reinforcing 80 bars, and consequently the gasometer bells, are simultaneously guided.

In the accompanying drawings are shown 85 by way of example two embodiments of the invention. In said drawings, Fig. 1 is a view in elevation, partly in section, of a telescoping gasometer composed of two bells and a bottom tank and constructed in accordance with the present invention; Fig. 2 is a perspective view of a detail on an enlarged 90 scale; Fig. 3 illustrates the application of my invention in connection with a spirally-guided telescopic gasometer and Fig. 4 is a detail of Fig. 3 on an enlarged scale.

The gasometer shown in Fig. 1 is composed of two bells *c*, *b*, and a bottom tank *a* which is fixed upon the ground, the two bells being movable vertically to vary the capacity 95 of the gasometer. The gasometer bells and tank are sealed against one another by the 100

sliding seals *d* and *e*. Each of these seals consists of an upper packing ring *f* or *f'*, a lower packing ring *g* or *g'* and a packing material confined between these rings. The packing material may for example consist of a semi-solid grease which simultaneously serves to lubricate the surfaces against which the seals slide. The bells and tank are built up of rectangular metal plates *p* equal in height to the respective bell or tank, the joints between the plates extending in the direction of movement of the bells, i. e. vertically; the rivets *r* connecting these plates are consequently arranged in rows extending in the direction of movement of the gasometer.

In order to insure a perfect seal between adjacent gasometer bells, and between the lowest bell and the tank, it is necessary that the contacting surfaces be as smooth as possible. This is not possible when rivets with raised heads are employed, as has heretofore been the practice. In accordance with the present invention bars or rails *h* and *i* are applied both at the interior and at the exterior of the joints between the plates, and the latter then riveted with sunken rivets *r* so that the outer surfaces of such bars are completely smooth. This construction is shown more clearly in Fig. 2. It will be seen from this figure that both the inner and the outer of any two adjacent gasometer bells are provided with the bars *h* and *i*. The packing rings *f*' and *g*' shown in this figure are cut out as indicated at *k* to receive the bars *h*. The fitting between the bars *h* and cut-outs *k* is made as close as possible so that the escape of gas or of sealing fluid is prevented, while at the same time the bars, and consequently the gasometer bells to which they are connected, are guided in their vertical movement. The bars *h* and *i* may be made of sufficient thickness to serve as reinforcing means so that if desired thinner plates may be used than could safely be employed without such bars. It will be understood that the bars *h* penetrate and extend through the associated seal as indicated in Fig. 2. These bars accordingly serve the triple function of providing a smooth surface for contact with the seals so as to form a gas-tight and grease-tight joint therewith, of acting as guide rails or posts to guide the gasometer bells in their telescoping movement, and finally, of reinforcing means for the several bells and the bottom tank. It will also be clear that the rings *f*, *g*, *f'*, *g'*, aside from their sealing function, serve also as guides for the bars *h*. Where a sliding seal is not employed, rings similar to the sealing rings, or ring segments, may be employed to guide the bars *h*.

In the case of telescoping gasometers of the type whose bells are guided for spiral movement, such as shown in Fig. 3, the rows of

rivets and the reinforcing iron bars *l* and *o* are arranged in the direction of such spiral movement. The packing rings for the gasometer sections are indicated at *m* and *n*, and at *m'* and *n'*. The cut-outs in these packing rings must lie along the spiral followed by the gasometer bells in their upward and downward movement and are therefore inclined to the vertical as shown at *q*, *q'* in Fig. 4. As the bars *l* and *o* are curved along the same spiral, they slide smoothly in these cut-outs and so form a continuously tight seal therewith. As in the embodiment shown in Figs. 1 and 2, the engagement of the bars within the cut-outs in the packing rings of the seals provides a simple, efficient and reliable guiding of the gasometer bells in their telescoping movements.

The plates *p* of which the bells and tank are composed are, like the plates shown in Fig. 1, equal in height to the height of such bells or tanks. This construction has the advantage over bells composed of two or more rings of plates that horizontal rows of rivets are eliminated and the sealing of the bells thereby simplified.

In the embodiment of the invention shown in Figs. 1 to 3 there have been illustrated by way of example telescopic gasometers in which each upper bell is of greater diameter than the next lower bell or the tank. The present invention, however, may be embodied with equal advantage in telescopic gasometers in which each upper bell is of smaller diameter than the next lower bell or tank. As the application of the present invention to gasometers of this latter type involves no departure from the principles above disclosed, illustration of the same is not considered to be necessary.

Variations from the specific forms of the invention illustrated may be made within the scope of the appended claims without departing from the spirit of the invention.

I claim:

1. A telescopic gasometer of the spirally moving type, comprising a plurality of bells, each composed of a plurality of joined plates equal in height to their respective bells, said plates being so formed that the joints therebetween lie along a spiral parallel to that followed by the bells in their telescoping movements reinforcing bars located at the joints of said plates and likewise extending along said spiral, and rivets passing through said bars and plates and connecting the same, said rivets being sunken to maintain the surfaces of said bars smooth for engagement by a sealing or guiding means.

2. A telescopic gasometer comprising a plurality of bells, each composed of riveted plates equal in height to their respective bells, said plates being so formed that the joints therebetween lie along a line parallel to the direction of movement of said bells, reinforc-

ing bars located at the joints of said plates and likewise extending along such line, sunk-en rivets connecting the plates to each other and to said bars, the faces of the bars receiv-
 5 ing the rivet heads being thereby maintained substantially smooth, and a guiding element located on one of each pair of adjacent bells and cooperating with the bars of the adja-
 10 cent bell to guide the bells in their telescop-
 10 ing movements.

3. A telescopic gasometer comprising a plu-
 rality of bells, each composed of riveted
 plates equal in height to their respective bells,
 said plates being so formed that the joints
 15 therebetween lie along a line parallel to the
 direction of movement of said bells, reinforc-
 ing bars located at the joints of said plates
 and likewise extending along such line, sunk-en
 rivets connecting the plates to each other
 20 and to said bars, the faces of the bars receiv-
 ing the rivet heads being thereby maintained
 substantially smooth, slidable sealing means
 carried by one of each pair of adjacent bells
 25 and positioned between such bells, said seal-
 ing means comprising spaced packing rings
 adapted to receive a sealing material in the
 space therebetween, said rings being provid-
 ed with cut-outs of the outline of said bars
 30 to receive the latter, whereby the gasometer
 bells are guided in their telescoping move-
 ments by the engagement of such bars in said
 cutouts and the seals between adjacent bells
 are undisturbed.

4. A telescopic gasometer comprising a plu-
 rality of bells each composed of individual
 plates of the height of the respective bells,
 rows of rivets connecting said plates, rein-
 forcing bars at the joints of the plates, said
 35 bars receiving said rows of rivets and said
 joints and bars extending in the direction of
 movement of the bells, said rivets being sunk-en
 to maintain the outer surfaces of said bars
 substantially smooth, and a sliding seal be-
 40 tween each pair of adjacent bells and includ-
 ing a sealing ring carried by one of such bells,
 the sealing rings being provided with cut-
 outs for receiving the bars of the adjacent
 bell, whereby the gasometer bells are
 45 strengthened by said bars and are guided by
 the engagement of such bars in said cut-outs.

Signed at Munich, Germany, this 11th day
 of July, A. D. 1929.

KONRAD JAGSCHITZ.
